(57) **CLAIM**

We claim the ornamental design for a display stand for an item of merchandise, as shown and described.

DESCRIPTION

FIG. 1 is a perspective view of an embodiment of a display stand for an item of merchandise showing our design;

FIG. 2 is a front view thereof;

FIG. 3 is a rear view thereof;

FIG. 4 is left side view thereof;

FIG. 5 is right side view thereof;

FIG. 6 is a top view thereof; and,

FIG. 7 is a bottom view thereof.

The broken lines are directed to environment and are for illustrative purposes only. The broken lines form no part of the claimed design.
